CONTAINER

Alexander G. Smirnoff, New York, N. Y.

Application January 22, 1941, Serial No. 375,372

7 Claims. (Cl. 220—47)

My invention relates to containers and has particular reference to containers or boxes for candy, cigarettes, buttons, and similar articles.

My invention has for its object to provide a container, particularly for candies, with an ornamental cover preferably made of a flexible material in the shape of a doll or similar human figure. I further provide the doll with a simple device for moving the dress up and to one side for opening the box, the movement being accomplished by depressing a portion of the doll, as, for instance, its head.

My invention is more fully described in the accompanying specification and drawing, in which:

Fig. 1 is a fractional sectional elevational view of my box;

Fig. 2 is a sectional plan view taken on the line 2—2 of Fig. 1 with the cover removed and the device in a closed position;

Fig. 3 is a fractional sectional view of the device taken on the line 3—3 of Fig. 1, showing the cover mechanism in a depressed or opening position, as indicated in dotted and dashed lines in Fig. 1;

Fig. 4 is a perspective view of the box in an opened position.

My container consists of a base 1 with a peripheral wall 2 forming a box open at the top and suitable for containing candy, cigarettes, and various other small articles. The base has a bracket 3 supporting a tubular post 4, in which slides a rod 5 which may be hollow to reduce its weight. A spring 6 normally keeps the rod in the raised position, as shown in Fig. 1. The upper end of the rod supports the head 7 of a doll 8 shown more fully in Fig. 4.

The doll or human figure 8 has a large dress or skirt 9 with a hoop 10 at the hem, the hoop loosely enclosing the box. The hoop may be reinforced with a metal wire 11, in order to make it sufficiently rigid, so that it will retain its circular shape. The doll with its dress forms, therefore, an effective cover for the box 1.

A mechanism is provided for raising the dress, thereby opening the box. The post 4 is provided for this purpose with a bracket 12 at the top supporting a pivot 13 for a lever 14. The latter is hingedly connected at 15 to the wire 11 of the hoop, the rear end of the lever having a curved hook 16 slidably engaged by a lug 17 attached to the rod 5. For opening the box, the doll's head is depressed, the lug 17 forcing the hook 16 downward and raising the lever, as shown in dotted and dashed lines in Fig. 1. As a result, the hoop 10 will be raised at one side, as shown in Fig. 4, providing a free access to the contents of the

box. The spring 6 moves the doll upward when the pressure on its head is released, thereby causing the hoop to be lowered over the box.

The doll may be of any convenient shape, the dress being preferably made of an ornamental fabric or other suitable flexible material. The doll may be complete with legs, covering the post 4.

The box may be of any suitable shape or form 10 and may be replaced by a stand for supporting various objects, such as ash trays, toilet accessories, etc.

The essential part of the cover is the flexible dress forming a hood over the box with the hoop 15 supporting the hem or lower edge of the dress. The dress and the doll may be therefore of any suitable form and may even represent a figure other than human, as, for instance, a hen or other bird sitting on a nest, or may even be made in a simplified form of a plain or ornamental cap or hood.

The box, when used as a container for selling candy and similar products, may be provided with a temporary paper cover over its upper edge, the 25 cover being destroyed for removing the contents.

It is understood that my container may be further modified without departing from the spirit of the invention, as set forth in the appended claims.

I claim as my invention:

1. A container comprising a base adapted to support removable articles, a post supported on the base, a member slidably supported on the post, means to urge the member upward, a hood supported on the sliding member, the lower portion of the hood loosely enclosing the base, and means to raise one side of the hood, by depressing the sliding member with the upper portion of the hood.

2. A container comprising a base adapted to support removable articles, a post supported on the base, a member slidably supported on the post, a spring urging the member upward, a flexible hood supported on the sliding member, the lower portion of the hood loosely enclosing the base, a hoop attached to the lower edge of the hood, and means to raise one side of the hoop, thereby tilting the hood and exposing the corresponding side of the base.

3. A container open at the top comprising a base adapted to support removable articles, a flexible hood removably supported over the base, the lower portion of the hood enclosing the articles, a rigid hoop attached to the lower edge of the hood, and means to raise one side of the hoop

with the hood by depressing the upper central portion of the hood, thereby exposing the articles.

4. A container comprising a base forming a bottom of a box open at the top, a tubular post supported on the base, a rod slidably supported in the post, a spring in the post urging the rod upward, a flexible hood supported on the upper end of the rod, the lower portion of the hood extending over the box, a lever rotatively supported at the post, the outer end of the lever being operatively connected to the hood, and operative connections between the lever and the rod, the outer end of the lever being adapted to be raised by depressing the rod, thereby raising the hood and exposing the contents of the box. 10

5. A container comprising a base forming a bottom of a box open at the top, a tubular post supported on the base, a rod slidably supported in the post, a spring in the post urging the rod upward, a flexible hood supported on the upper end of the rod, the lower portion of the hood extending over the box, a lever rotatively supported at the post, a hoop attached to the lower edge of the hood and loosely enclosing the box, the outer end of the lever being hingedly connected to the hoop, and a lug on the rod operatively connected to the lever and adapted to raise 15

the outer end of the lever when the rod is depressed, thereby raising one side of the hoop with the hood and exposing the contents of the box.

6. A container open at the top comprising a base adapted to support removable articles, a post supported on the base, a member slidably supported on the post, means to urge the member upward, an ornamental figure supported on the upper end of the sliding member, a flexible hood extending from the figure over the base, a hoop attached to the lower edge of the hood loosely encircling the base, and a lever connecting the sliding member with one side of the hoop adapted to cause one side of the hoop to be raised above the container when the figure with the sliding member is moved downward. 10

7. A container comprising a base forming a bottom of a box open at the top, a tubular post supported on the base, a rod slidably supported in the post, a spring in the post urging the rod upward, a doll's head and torso supported on the upper end of the rod, a flexible dress extending from the doll over the box, a hoop attached to the hem of the dress loosely encircling the box, and means to raise one side of the hoop above the box by depressing the doll's head. 20
